(57) **CLAIM**

The ornamental design for an electric outboard motor, as shown and described.

DESCRIPTION

FIG. 1 is a front, left-side, and upper view showing the new design;

FIG. 2 is a rear, right-side, and upper view thereof;

FIG. 3 is a front, right-side, and lower view thereof;

FIG. 4 is a right-side elevation view thereof;

FIG. 5 is a left-side elevation view thereof; and,

FIG. 6 is a front elevation view thereof.

The broken lines shown in the drawings are for the purpose of illustrating portions of the depicted article and form no part of the claimed design.
